UNITED STATES PATENT OFFICE.

SETRAK G. EGHAN, OF OGDEN, UTAH.

COLLAR-FASTENER.

No. 922,682.

Specification of Letters Patent.

Patented May 25, 1909.

Application filed July 17, 1907. Serial No. 384,133.

To all whom it may concern:

Be it known that I, SETRAK G. EGHAN, a citizen of the United States, residing at Ogden, in the county of Weber and State of Utah, have invented certain new and useful Improvements in Collar-Fasteners, of which the following is a specification.

My invention relates to clasps or fastening appliances, to be used especially in securing 10 collars of soft material to waists, worn principally by women.

The invention may be made available in other applications, however, such for example, as a fastener for cuffs.

15 In the accompanying drawing Figure 1 is a front view of the clasp; Fig. 2 an end view; Fig. 3, a view of the pin; Fig. 4 a rear view of the clasp in position in a waist and collar ready to receive the pin; and Fig. 5 a cross-20 sectional view of the clasp and pin in position.

The clasp has a flat metal body 1, the smooth side of which lies against the neck of the wearer. A plurality of fingers 2, preferably two in number, one near each end of the clasp, are conveniently formed integrally with the body. The fingers terminate in loops or eyes 3, which are considerably separated from the body, as seen in Fig. 2.

30 Referring to Fig. 4, the neck-band of waist, 4, has in each side a small button-hole through which the lower of fingers 2 is passed. Collar 5 has also at top and bottom of each end a similar button-hole. The bottom and 35 top button-holes of one end of the collar are hooked over corresponding fingers 2, the collar passed around the neck, and the other button-holes put over the fingers, as seen in the figure. The clasp is now ready for the 40 pin. An ordinary safety pin may be employed, but for decorative purposes a special pin is preferred, as illustrated in Fig. 3.

The body 6 of the pin may be shaped to correspond with the body of the clasp, or 45 may vary therefrom in outline. Pivoted to the body at one end is the pin-shank 7, of a size which will pass easily through eyes 3, and preferably flat. Spring hook 8 on the body serves to hold the shank in closed position.

50 The clasp being in position as shown in

Fig. 4, and the pin-shank being open as in Fig. 3, the shank is passed downward through eyes 3, and the pin body 6 then swung on the pivot until spring hook 8 engages the shank, when all parts are locked in position. The 55 pin-shank prevents the button-holes from coming off of fingers 2.

In addition to its stated function, it is to be noticed that the clasp also serves as a distance piece, or stretcher, holding up the top 60 edges of the collar (which is generally of soft or unstarched material) at the back, and preventing sagging at this point.

Considerable variations in points of detail may be made without departing from the 65 spirit of my invention.

I claim:

1. The combination of a clasp comprising a body and two separated fingers thereon adapted to engage garment button-holes, and 70 a pin coöperating with the clasp, having a shank adapted to engage both of the fingers and retain the clasp in operative relation to the garment.

2. The combination of a clasp comprising 75 a body and two separated fingers thereon terminating in eyes and adapted to engage garment button-holes, and a pin coöperating with the clasp, having a shank adapted to pass through both of the eyes and retain 80 the clasp in operative relation to the garment.

3. The combination of a clasp comprising a body and two separated fingers thereon terminating in eyes and adapted to engage 85 garment button-holes, and a pin coöperating with the clasp comprising a body, a shank pivoted to the body near one end, and a hook to secure the free ends of the shank, the shank being adapted to enter the eyes 90 and prevent displacement of members of the garment from the clasp.

In witness whereof I have hereunto set my hand in the presence of two subscribing witnesses.

SETRAK G. EGHAN.
